FLEXIBLE CAR ROOF

Kenneth J. Tobin, Chicago, Ill., assignor, by
mesne assignments, to The Youngstown Steel
Door Company, Cleveland, Ohio, a corporation
of Ohio

Application April 5, 1934, Serial No. 719,088

8 Claims. (Cl. 108—5)

This invention relates to flexible car roofs.

It is an object of this invention to provide a flexible car roof which shall be lighter in weight, involve a substantial reduction in cost and effect 5 a savings in parts and cost of the roof sub-structure than those flexible roofs now in general use upon railway freight cars.

A further object is to provide a flexible jointless car roof.

10 A further object is to provide a flexible car roof utilizing a fabric outer covering.

A further object is to provide a flexible car roof capable of rapid repair in situ.

15 A further object is to provide a flexible car roof having a fireproof nonmetallic outer covering.

A further object is to provide a flexible car roof having a fireproof and weatherproof nonmetallic outer covering.

20 A further object is to provide a flexible car roof which shall practically eliminate condensation upon the inside of the roof without the necessity of inside insulation therefor.

A further object is to provide a flexible car 25 roof which shall present enhanced dust, weatherproof and wearing qualities.

A further object is to provide a flexible car roof which can readily be applied over an existing roof.

30 A further object is to provide a flexible car roof which permits of a substantial reduction in the numbers of parts to be carried in stock.

A further object is to provide a running board 35 for railway freight car roofs which shall be strong, easily applicable, fireproof, and which shall comprise a metallic base and plastic filler having a roughened outer surface.

Other objects of the invention will become clear as the description thereof proceeds.

40 In the drawings forming part of this specification

Figure 1 is a broken plan view of a car roof embodying the invention;

45 Figure 2 is a horizontal section taken on line 2—2 of Figure 1;

Figure 3 is a view similar to Figure 2, showing a portion of the roof and running board construction on an enlarged scale;

50 Figure 4 is a partial vertical section taken on line 4—4 of Figure 2;

Figure 5 is a partial horizontal section taken on line 5—5 of Figure 3;

55 Figure 6 is a horizontal section similar to Figure 4 through the opposite end of the car roof and framing structure;

Figure 7 is a fragmentary vertical section taken on line 7—7 of Figure 2;

Figure 8 is a horizontal section similar to Figure 2 of a portion of the roof adjacent the eaves on an enlarged scale;

5 Figure 9 is a view similar to Figure 8 showing a modified form of side plate; and

Figure 10 is a vertical section taken on line 10—10 of Figure 2.

Referring to Figure 1 of the drawings, applicant's novel car roof is designated in its entirety by the reference numeral 10. A pair of side plates 11 and 12 are shown disposed at the eaves of the roof. Each of these side plates is substantially Z shaped in section as indicated in 15 Figures 2 and 8 of the drawings. The side plates are so disposed that one flange 13 thereof extends horizontally and inwardly relative to the roof while the other flange 14 extends horizontally and outwardly relative thereto. The web 20 15 is disposed vertically.

A plurality of longitudinally spaced carlines 16 extend from side plate to side plate, as clearly shown in Figure 1 of the drawings, and have their ends secured to the inwardly extending 25 flanges 13 of said side plates. Each of the carlines is preferably of substantially channel shaped section and comprises a web 17 (see Figure 7) from which the sides 18 and 19 depend. Each of these sides is bent in opposite directions 30 in order to provide flanges 20 and 21. Transversely spaced purlins 22 extend from end to end of the roof and between the carlines. These purlins are secured to the flanges 20 and 21 of the carlines as by means of bolts 23. To permit such 35 securing the purlins are formed with shoulders 24 and 25 Fig. 2 through which the securing bolts 23 extend. The upper surface of the purlins, as clearly shown in Figure 7 of the drawings, is aligned with the upper surface of the webs 17 40 of the carlines.

One form of end construction is illustrated in Figure 4 of the drawings. This construction is utilized where it is desired to employ doors at the end of a car. The construction embodies a 45 substantially channel shaped end plate 26 which comprises the spaced vertically depending legs 27 and 28 connected by means of a web 29. The outwardly disposed leg 27 has secured thereto a Z shaped framing member 30, one leg 31 of which 50 is disposed vertically and serves as a framing member for a door (not shown). A wooden member 32 is secured to the outer face of the vertical leg 27 which, in addition, carries an angular plate 33 adapted to shed water outwardly of the end 55

door. A cap member 34 secured at one end to the wooden member 32 is utilized in connection with the end plate 26. The cap member is provided with a vertically depending leg 35, the lower end of which is bent so as to constitute a flange 36. The inwardly disposed vertical leg 28 of the end plate is bent inwardly to provide a flange 37 to which a substantially Z shaped bracket member 38 is secured. The adjacent 10 ends of the purlins 22 are adapted to be supported upon the bracket 38 and to be secured thereto as by means of bolts 39.

Where a solid end is employed in a railway freight car the construction illustrated in Figure 15 6 of the drawings may be utilized. It is to be understood that where both ends of a railway freight car utilize solid ends the construction shown in Figure 6 may be utilized at both such ends. In the solid end illustrated an end plate 20 40 is employed. At its upper margin the plate is bent inwardly so as to constitute a flange 41 to which a substantially Z shaped bracket member 42 is secured. This bracket member is adapted to support the adjacent ends of the 25 purlins 22 which are secured to said bracket member as by means of bolts 43.

The structures above described may be deemed to constitute a frame upon which applicant's 30 novel roof construction is laid. For this purpose a pair of spaced angular members 44 and 45 preferably L shaped in section, are secured to the webs of the carlines 16 and extend substantially between the end structures above described. Figure 2 of the drawings illustrates approximately one-half of the horizontal section of the roof so that it will be apparent that in the preferred construction a pair of angle members 44 and 45 is secured on each side of the longitudinal center line of the roof. It is to be understood, however, that angular members may be secured adjacent the eaves only of the roof framing structure. Between the angle members 44 and 45 a reticulated metallic base 46 is disposed. This base, as clearly shown in Figures 40 45, 1, 2, 4 and 6, extends continuously between the angular members 44 and 45 and the end structures. In its application to the framing construction the reticulated metallic base is placed under tension and secured to the upstanding 50 legs 47 and 48 of the angular members 44 and 45. A preferred form of securement of said base to the angular members utilizes spaced slots 49 provided in the upstanding legs 47 and 48 of the angle members. The bonds at one side of the 55 reticulated metallic base formed by the strands of wire of which said base is constituted are disposed within the spaced slots 49 of the upstanding leg 48 of the angular member 45, said bonds being then bent in opposite directions to provide 60 engaging prongs 50 in order to fasten the corresponding side of the base to the upstanding leg 48. To maintain this securement the upstanding leg may be deformed as indicated at 51. The metallic base 46 is then tensioned and the bonds 65 at the opposite side of said base engaged in slots formed in the upstanding leg 47 of the angle member 44 whereupon portions of said bonds are bent in opposite directions in order to fasten said base to the angle member 44. Disengagement from the angle member 44 is prevented by the deformation of the upstanding leg 47, as clearly indicated in Figure 8 of the drawings. It will be apparent from the foregoing that the reticulated metallic base on each side of the longitudinal center line of the roof is securely fas-

tened to the roof frame under tension. It will also be apparent that the same procedure may be followed where the metallic base extends continuously from eaves to eaves of the roof. At each of the end constructions above described the metallic base is fastened by means of bars 52 and 53 which are disposed within the loops provided by the reticulated metallic base, as clearly shown in Figure 5 of the drawings. At the end construction shown in Figure 4 of the drawings 10 the bar 52 is fastened to the inwardly directed flange 37 of the end plate 26 by means of bolts 54 which extend preferably through a wooden filler member 55. At the end structure shown in Figure 6 of the drawings the bar 53 is fastened 15 to the inwardly directed flange 41 of the end plate 41 by means of bolts 56 which extend preferably through a wooden filler 57 disposed upon said inwardly directed flange.

The reticulated metallic base being placed under initial tension and secured to the roof frame adds materially to the rigidity of the roof and thus permits the elimination of substantially half the carlines heretofore used in flexible railway car roofs. In roofs of this type, standard practice employs 13 carlines in cars having an inside length of 40' 6", whereas in applicant's construction substantially 7 carlines are sufficient. By his invention applicant obtains a reduction in the weight of the car roof and a reduction in 30 cost as well, in addition to the attainment of the objects heretofore enumerated.

Upon the above described base a flexible covering 58 is disposed, said covering being preferably seamless and of such extent as to completely 35 cover the base from eaves to eaves and end to end. The flexible covering utilized is preferably a rubberized fabric which permits flexing of said fabric in response to the weaving and racking of the car and which is weatherproof. In its application the covering 58 is secured to the eaves and the ends of the roof structure under tension. This tension may be applied mechanically during the securement of said covering although it is contemplated and preferred that the fabric be 40 placed under tension as hereinafter described.

With reference to Figures 2 and 8 of the drawings there is illustrated one mode of securement of the fabric to the eaves. In the accomplishment of this securement the fabric is extended 50 downwardly so as to overlie the vertical web 15 of each of the side plates 11 and 12. The fabric is extended downwardly over a filler member 59 preferably of wood secured to the inwardly directed flange 13 of the side plates. A plate 55 member 60 provided with a rounded edge 61 is disposed upon the margin of the downwardly extending portion of the fabric so as to lie upon the under face of said fabric with the rounded edge thereof remote from the adjacent edge of 60 the fabric. Bolts such as 62 are then extended through aligned openings provided in said margin of the fabric and said plate whereupon said plate and fabric are folded upwardly so that the fabric is bent around the rounded edge of the plate 65 60 and the heads 63 of the bolts are disposed between the fabric and the plate. The bolts are then extended through openings provided in the vertical web of each of the side plates 11 and 12 and nuts applied to the ends thereof in order 70 to securely fasten the depending portion of the fabric to the side plates. It will be apparent that with this mode of securement of the fabric to the side plates the heads of the bolts will be protected.

At the end structure shown in Figure 4 of the drawings the fabric is bent upwardly as indicated at 64 so as to lie against the vertical leg 28 of the end plate 26. A metallic plate 65 is placed against the fabric whereupon said plate and fabric may be fastened to the leg 28 of the end plate by means of rivets 66. The upturned portion of the fabric is protected against the weather by means of the cap member 34, the 10 flange 36 of which is disposed upon the fabric.

At the end construction illustrated in Figure 6 of the drawings the fabric is extended downwardly around a wooden member 67 and secured to the end plate 40 by means of bolts 68 which extend through the wooden member 67 in the manner hereinabove described for the securing 15 of said fabric to the eaves.

After the fabric has been applied as hereinabove indicated it is preferred to paint said fabric with any well known or desired substance which shall have the capacity of shrinking said fabric tightly upon the roof. This shrinkage so imparted to the fabric places said fabric under tension so that the fabric is adapted to accommodate itself to the distortions to which the roof may be subjected. The fabric may then be painted with any well known or desired paint which has the property of forming a mineral deposit upon the fabric so as to render it fireproof or, 20 if desired, a paint having this characteristic may be incorporated in the substance spread upon the fabric in order to shrink it. If desired the fabric may be coated in any other way in order to render it fireproof.

35 In Figure 9 of the drawings there is illustrated a modified form of side plate which may be utilized with applicant's roof above described. This side plate designated by the numeral 69 is substantially Z shaped in section and is disposed 40 with its flanges 70 and 71 arranged vertically and its connecting web 72 arranged horizontally. The upwardly extending vertical flange 71 is deformed so as to present a flange 73 adapted to support the wooden member 74 about which the fabric is 45 bent downwardly. The fabric of applicant's roof may be secured to the vertical flange 71 of the side plate 69 in the same manner utilized for the securing of the fabric to the side plates 11 and 12.

50 With the above described novel roof applicant prefers to utilize his novel running board structure. The running board is supported by means of a plurality of saddles 75 which are bolted to the web 17 of the carlines 16. In the construction 55 shown in Figures 2, 3, and 10 of the drawings wooden blocks 76 are preferably interposed between the saddles and the carlines 16. The fabric 58 of the roof lies upon the wooden filler blocks 76 and in order to protect this fabric against injury by the saddles 75 a strip of canvas is disposed between said saddles and the fabric. Each 60 of the saddles 75 is preferably U shaped in section and provided with the oppositely extending flanges 77 and 78 to which the running board 65 is bolted.

The running board comprises a metallic base 79 provided with upstanding side flanges 80 and 81 and upstanding end flanges 82 and 83. The running board thus presents a substantially pan 70 shaped construction which may be filled with a plastic substance or any other desired substance suitable for the purpose to provide a tread upon which trainmen may walk. It is preferred to utilize asphalt, indicated at 84, the upper surface 75 of which is roughened as shown at 85. For this

purpose slate or any other desired comminuted mineral particles imbedded in the asphalt may be utilized. A ridge pole is indicated at 86, said ridge pole being of substantially U shaped section having oppositely directed flanges, one of 5 which is illustrated at 87 in Figure 2 of the drawings, secured to the flanges 20 and 21 of each of the carlines 16. An aperture 88 is formed in said ridge pole in order to expedite securing 10 of the saddles 75 to the carlines 16.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A flexible railway freight car roof comprising transversely spaced longitudinally extending 20 angle members each arranged with one leg upstanding, spaced slots formed in said leg, a reticulated metallic base having spaced prongs disposed in said slots, said prongs being bent into engagement with said upstanding legs to fasten 25 said base to said angle members, said base being fastened to said angle members under tension and a nonmetallic waterproof and fireproof tensioned fabric covering upon said base.

2. A flexible railway freight car roof comprising transversely spaced longitudinally extending angle members each arranged with one leg upstanding, spaced slots formed in said leg, a tensioned reticulated metallic base having portions engaged in said slots, said legs being deformed to 30 maintain said engagement and a nonmetallic waterproof and fireproof tensioned fabric covering upon said base.

3. A flexible railway car roof comprising a frame including side and end plates defining the 40 sides and ends of said frame and spaced transverse carlines extending between and secured to said side plates, a reticulated metallic base supported upon said frame, means securing said reticulated base to said frame at the sides thereof, 45 means securing said base to said frame at the ends thereof, said base being drawn taut to place said base under initial tension and a non-metallic flexible covering secured upon said metallic base.

4. A flexible railway car roof comprising a 50 frame including side and end plates defining the sides and ends of said frame and spaced transverse carlines substantially less in number than normally utilized in flexible car roofs extending between and secured to said side plates, a reticulated metallic base supported upon said frame, means securing said reticulated base to said frame at the sides thereof, 55 means securing said base to said frame at the ends thereof, said base being drawn taut to place said base under initial tension and a non-metallic flexible covering secured upon said metallic base.

5. A flexible railway car roof comprising a frame including side and end plates defining the 65 sides and ends of said frame and spaced transverse carlines extending between and secured to said side plates, longitudinally extending members secured to said carlines adjacent the ridge of said frame, metallic mesh extending from end to end 70 of said frame and between said members and the adjacent sides of said frame, means securing said mesh to said longitudinally extending members and to said frame at the ends and sides thereof, 75 said mesh being drawn taut to place said mesh

under initial tension and a non-metallic fabric covering secured upon said mesh.

6. A flexible railway car roof comprising a frame including side and end plates defining the sides and ends of said frame and spaced transverse carlines substantially one-half in number of the carlines normally utilized in flexible car roofs extending between and secured to said side plates, a reticulated metallic base supported upon said frame, means securing said reticulated base to said frame at the sides thereof, means securing said base to said frame at the ends thereof, said base being drawn taut to place said base under initial tension and a non-metallic flexible covering secured upon said metallic base.

7. A flexible railway car roof comprising a frame including side and end plates defining the sides and ends of said frame and spaced transverse carlines extending between and secured to said side plates, a reticulated metallic base supported upon said frame, means securing said reticulated base to said frame at the sides thereof,

means securing said base to said frame at the ends thereof, said base being drawn taut to place said base under initial tension and a non-metallic flexible covering secured upon said metallic base, said flexible covering being drawn taut to place it under initial tension.

8. A flexible railway car roof comprising a frame including side and end plates defining the sides and ends of said frame and spaced transverse carlines extending between and secured to said side plates, longitudinally extending metallic members secured to said carlines adjacent the ridge and the sides of said frame, metallic mesh extending from end to end of said frame and between said longitudinally extending members, means securing said mesh to said members and said ends of said frame, said mesh being drawn taut to place said mesh under initial tension and a non-metallic flexible fabric covering disposed upon said mesh and secured to said side and end plates.

KENNETH J. TOBIN.
